SWITCH ADAPTER FOR PROVIDING SELECTIVE OPERATING CONDITIONS FOR THE SWITCH
William Ray Brown, Indianapolis, Ind., assignor to P. R. Mallory & Co. Inc., Indianapolis, Ind., a corporation of Delaware

Filed Oct. 6, 1966, Ser. No. 584,768
8 Claims. (Cl. 200—172)

ABSTRACT OF THE DISCLOSURE

An adapter for a switch which provides selective operating conditions for the switch.

This invention relates to snap action mechanisms, and particularly to an adapter for snap switches.

Snap action mechanisms have found great utility in recent years since they are relatively simple and economical to actuate the mechanisms with which they are associated with a positive stroke of the snap blade even though the force which acts to actuate the mechanisms is applied very slowly. More particularly such snap action mechanisms have found particular utility in the electrical field in the form of snap and/or double throw snap action switches since the quick snapping action of the snap blade associated with the mechanism is effective to substantially eliminate arcing between two adjacent contacts.

In switches such as these, adapters are usually required so that the switch may be readily actuated in accordance with predetermined requirements. The present invention provides for such an adapter and has as one of its foremost objects the provision of means to provide either a momentary electrical impulse or a permanent electrical contact.

Another object of the invention is to provide such an adapter which is small and compact.

Another object of the invention is to provide such an adapter which is easily aligned with the switch.

Yet another object of the invention is to provide such an adapter wherein a single actuator bar actuates the switch button.

Another object of the invention is to provide such an adapter which utilizes a return spring to bias the actuator bar.

Still another object of the invention is to provide such an adapter wherein the actuator bar and the return spring are disposed within a two piece cover and wherein the pieces are held together by staking thus, rendering the adapter susceptible to a plurality assembly.

With the above and other objects in view, which will appear as the description proceeds, this invention resides in a novel construction combination and arrangement of parts substantially as hereinafter described and more particularly defined by the appended claims, it being understood that such changes in the precise embodiment of the invention here disclosed may be made as come within the scope of the claims.

In the accompanying drawings:

FIGURE 1 is a perspective view of a bank of the adapters attached to and made part of a corresponding bank of switches;

FIGURE 2 is an exploded view of the novel adapter showing its relationship with a switch;

FIGURES 3 and 4 are side views of the adapters taken along the line 3—3 of FIGURE 1, with portions of the adapter being in cross-section; and

FIGURE 5 is a section taken along line 5—5 of FIGURE 3.

Generally speaking, the objects of the invention are accomplished by providing an adapter for a switch, which in the main, comprises spring biased actuating means

2

adapted to selectively engage the actuating means of a snap switch. More particularly, the adapter comprises a spring biased actuator bar having a cam surface adapted to engage a snap switch button having a cam follower surface such that when a selective external force is applied to the actuator bar the switch button is correspondingly selectively actuated. Such selective actuation of the actuator bar permits either a momentary electrical impulse or a permanent electrical contact.

In its preferred construction as shown by the drawings, the adapter comprises a cover preferably constructed in two identical sections, the cover being adapted to be fastened to a snap switch. The snap switch has a switch button extending through the housing of the snap switch through an aperture formed in the housing. The button has a cam follower surface on the end extending from the housing. Each of the sections forming the adapter's cover have notches centrally formed in their abutting edges to form an opening in the cover. An actuator bar comprising a knob, a shank portion connecting the knob to a base, and a cam extending from the opposite surface of the base, extends through the opening in the cover, with the base being held in bearing relationship with the underneath side of the cover by a return spring disposed over the switch button of the snap switch. The return spring has a slot through which the cam of the actuator bar extends so as to be in actuating relationship with the cam follower surface of the switch button. To operate the snap switch for a momentary electrical impulse the actuator bar is pushed in causing the cam of the actuator bar to depress the switch button. For a permanent electrical contact, the bar is pushed forward causing the button switch to be permanently depressed through the movement of the cam against the cam follower surface of the button.

The sections of the cover are joined together through staking such that a bank of adapters can be readily adapted to a corresponding bank of switches.

Referring now to FIGURE 1, there is shown a bank 40 of the novel adapters 10 attached to a corresponding bank of snap switches 11 by means hereinafter described. Each of the adapters has a cover 12 which, for each of assembly, is composed of two identical sections 13 and 14. The separate adapters are staked together through 45 dowel pins 15.

Referring to FIGURE 2, a typical snap switch 11, for which the novel adapter is suitable, is composed of a housing 16 which is preferably, for ease of assembly, divided into two sections 17 and 18. A switch button 19 having a cam follower surface 20 extends through aperture 21 of the housing 16. Electric terminal leads 22 also extend from the housing and are in electrical contact with suitable switching blades located within the housing. Switch button 19 is also connected to such switching blades. Both the housing 15 and the switch button are fabricated from an electrical insulating material such as a thermosetting resin plastic, for example, as is the cover 12 of the adapter.

As previously stated, the cover 12 for the adapter is composed of two identical sections 13 and 14. The two sections are attached to section 18 of switch cover 16 through the pins 23 onto which slots 24 and 25 and their counterparts of section 13 are mated. Pins 23 have a flanged top portion 23a such that the sections 13 and 14 can be securely held to the switch housing. The sections of the cover are staked together in a manner more clearly shown in FIGURE 5.

Referring to FIGURE 5, section 13 has a bore 13a into which extension 14a of section 14 is received with a snug fit. Additionally bore 13a has a chamfer 13b such that the ends 14b of the extension can be flared upon

the application of heat. Section 14 also has a bore 14b through which the dowel pins 15 are passed.

Returning to FIGURE 2, the abutting edges 26 and 27 of sections 13 and 14 respectively have notches 28 and 29 cut in them in spaced relation such that opening 30 (FIGURE 1) is formed in cover 12 of the adapter. Actuator bar 31 which actuates the switch button 19 extends through this opening.

Actuator bar is made up of three sections: a base 32, a shank portion 33 connecting the base 32 to knob 34, and cam 35 extending from the opposite surface of the base. The bar may be of a one piece construction, and is fabricated from an electrical insulating material such as that used for the cover of the adapter and the housing for the switch. The actuator bar is carried by a return spring 36 having a slot 37 through which cam 35 extends. The return spring is positioned over switch button 19 such that cam 35 can be engaged with the cam follower surface 20 of button 19. This can be more readily seen with reference to FIGURES 3 and 4.

Referring to FIGURES 3 and 4, the actuator bar is carried by the return spring 36, the spring being biased such that when the spring is in its relaxed position the base 32 is held against the inner or underneath surface 38 of the adapter cover 12. The spring slidably rests on the surface 39 of switch housing section 18 such that cam 35 is substantially in alignment with switch button 19 such that the cam can readily be engaged with the cam follower surface 20.

In operation and with specific reference to FIGURE 3, a permanent electrical contact is made in the switch 11 by pushing knob 34 in the direction of the arrow. This moves cam 35 over cam follower surface 20 to the position 40. Likewise, return spring 36 assumes a new position 41. Thus, the switch button is depressed to position 42, and since the cam 35 is positioned over the button 19 as shown, a permanent electrical contact is made in the switch. That is, the contact is permanent until the knob 34 is pushed back to its original position.

Referring to FIGURE 4, when knob 34 is depressed in the direction of the arrow, the actuator bar is pivoted against point P where the base 32 bears against the inner surface 38 of cover 12. As cover 35 moves over cam follower surface 20 of button 19, the button is depressed. When the knob is released, return spring 36 moves the actuator bar back to its original position. Thus, a momentary electrical impulse is achieved.

From the foregoing description, taken in conjunction with the accompanying figures of the drawing, it will be readily apparent to those skilled in the art that this invention provides a new and improved adapter for snap switches, the principles of which may be applied to other similar devices. Accordingly, it is contemplated that the scope of the invention is to be determined from the following appended claims.

What is claimed is:

1. An adapter means for a switch providing selective operating conditions for said switch comprising: an apertured housing, an actuator bar seated in said aperture including means positioned without said housing and cam means positioned within said housing, said cam means adjacent a switch button of said switch means, spring bias means seated between said switch and said actuator bar for biasing said actuator bar away from said switch button, displacement of said actuator bar along one path causing said cam to engage with and displace said switch button, said actuator bar locked in position by the interaction between said housing and said actuator bar and said switch button when displaced along said one path providing a selective operating condition for said switch, displacement of said actuator bar along a different path causing said actuator bar to displace said spring bias means storing energy therein and said cam to engage with and displace said switch button providing another selective operating condition for said switch, release of said

stored energy of said spring biasing means displacing said actuator bar to said position adjacent said switch button.

2. An adapter means for a switch as claimed in claim 1, wherein said spring bias means is a slotted substantially U-shaped spring having extremities slidably engaging said switch, said cam extending through said slot.

3. An adapter means for a switch as claimed in claim 1, wherein said actuator bar includes a base engaging with a surface of said housing when said actuator bar displaces said switch button to said selective operating condition and base pivoted against said surface of said housing as said actuator bar displaces said switch button said other selective operating condition.

4. An adapter means for a switch providing selective operating conditions for said switch comprising: an apertured housing, an actuator bar seated in said aperture including a knob positioned without said housing and cam means and a base positioned within said housing, said cam means adjacent a switch button of said switch means, a slotted substantially U-shaped spring having extremities slidably engaging said switch seated between said switch and said base of said actuator bar for biasing said actuator bar away from said switch button, said cam projecting through said slot of said spring, displacement of said actuator bar along one path causing said cam to engage with and displace said switch button, said actuator bar locked in position by the interaction between said housing and said base of said actuator bar and said switch button when displaced along said one path providing a selective operating condition for said switch, displacement of said actuator bar along a different path pivoting said base of actuator bar about a point on said housing causing said base to displace said spring storing energy therein and said cam to engage with and displace said switch button providing another selective operating condition for said switch, release of said stored energy of said spring displacing said actuator bar to said position adjacent said switch button.

5. An adapter for a snap switch which provides for selective actuation of such switch such that either a momentary electrical impulse or a permanent electrical contact can be made by the switch, said adapter comprising:

(a) a cover composed of two identical sections, each section being adapted to be fastened to a snap switch, each of said sections having abutting edges and notches cut in said edges in spaced relation so as to form an opening in said cover,

(b) an actuator bar extending through said opening, said bar comprising a knob disposed outside said cover, a shank portion connecting said knob to a base disposed within said cover, and a cam extending from the opposite surface of said base,

(c) said actuator bar being carried by a return spring disposed within said cover and having a slot through which said cam of said actuator bar extends, said spring being slidably resting on the surface of the housing of said switch and being positioned over a switch button having a cam follower surface such that said cam can be engaged with said follower surface,

(d) said base of said actuator bar being biased against the underneath surface of said cover when said spring is in its relaxed position.

6. A bank of adapters for a corresponding bank of snap switches wherein each of said adapters comprises a cover, said cover being adapted to be fastened to a snap switch, a spring biased actuator bar extending through an opening in said cover, said bar having a base portion, said base portion being biased against the underneath surface of said cover when said spring is in its relaxed position, said bar being adapted to engage a switch button of said snap switch, said cover being composed of two identical sections with each section having

means to stake said sections together so as to form a bank of said adapters for a corresponding bank of snap switches.

7. A bank of adapters for a corresponding bank of snap switches wherein each adapter provides for selective actuation of a corresponding switch such that either a momentary electrical impulse or a permanent electrical contact can be made by the switch and wherein each of said adapters comprises:

- (a) a cover composed of two identical sections, each section being adapted to be fastened to a snap switch, each of said sections having abutting edges and notches cut in said edges in spaced relation so as to form an opening in said cover, 10
- (b) an actuator bar extending through said opening, said bar comprising a knob disposed outside said cover, a shank portion connecting said knob to a base disposed within said cover, and a cam extending from the opposite surface of said base, 15
- (c) said actuator bar being carried by a return spring disposed within said cover and having a slot through which said cam of said actuator bar extends, said spring being slidably resting on the surface of the housing of said switch and being positioned over a switch button having a cam follower surface such 20
- 25

that said cam can be engaged with said follower surface,

- (d) said base of said actuator bar being biased against the underneath surface of said cover when said spring is in its relaxed position,
- (e) each of said sections of said cover having means to stake said sections together so as to form said banks of said adapters for said corresponding snap switches.

8. A bank of adapters according to claim 7 wherein said means to stake said sections together comprises an extension extending from one of said sections, a bore running through said extension and said section, a bore in the other of said sections adapted to snugly receive said extension, and having a chamfer at its end opposite that of said other sections, said extension being flared at its extremity so as to mate said chamfer, and a dowel pin running through said sections.
